UNITED STATES PATENT OFFICE.

CHARLES ADAMS, OF UNION HILL, NEW JERSEY, ASSIGNOR OF ONE-HALF TO SYDNEY F. WESTON, OF NEW YORK, N. Y.

FIRE-EXTINGUISHING APPARATUS.

1,259,468.

Specification of Letters Patent. Patented Mar. 19, 1918.

Application filed October 18, 1916. Serial No. 126,259.

To all whom it may concern:

Be it known that I, CHARLES ADAMS, a citizen of the United States, residing in Union Hill, in the county of Hudson and 5 State of New Jersey, have invented certain new and useful Improvements in Fire-Extinguishing Apparatus, of which the following is a specification.

This invention relates to a fire extinguishing system in which a tank of non-combustion supporting substance is provided and 10 in which the formation of a gas by the combination of an acid with a salt or the like is utilized to exercise a pressure on the fire 15 extinguishing substance and itself to be thereby extruded for extinguishing a fire.

One of the main objects of the present invention is to provide a system in which the generation of a gas will be initiated by 20 the rise of temperature adjacent to an element of the system.

To this end the invention contemplates the provision of a tank provided with a substance that is in itself a fire extinguishing 25 element and in addition contains substance that has a great affinity for acid to form a gas whereby the fire extinguishing substance may be extruded from the aforesaid tank, the acid being contained in a receptacle separate from the tank and the flow 30 of the acid to said tank being caused by the well-known siphon action which is initiated by a decrease of pressure brought about by a discharge from certain outlets that are 35 held under control until the temperature adjacent thereto is raised to the melting point of the substance forming the closures of such outlets.

One of the main features of the present 40 invention is the provision of means whereby the various parts of the apparatus will be maintained under an equal pressure and in which the initiation of the action is brought about by disturbing this equalization of pressure.

Another particular feature of the present invention is the provision of means whereby the acid is siphoned into the tank containing the fire extinguishing element.

Another feature of the present invention 50 is an arrangement which readily adapts itself to be used either as a dry system or a wet system, the dry system contemplating the use of gas pressure for maintaining the required pressure, and the wet system con-

templating the use of a liquid for maintaining the required pressure.

These and other features, capabilities and advantages of the invention will appear from the subjoined detail description of 60 specific embodiments thereof illustrated in the accompanying drawings, in which—

Figure 1 is a diagrammatic elevational view, partly in section, of an embodiment equipped to be used either as a wet system 65 or as a dry system.

Fig. 2 is a diagrammatic elevational view, partly in section, of an embodiment especially adapted for use as a wet system.

In the embodiment illustrated in Fig. 1, 70 there is provided an enlarged elongated tank 1, an acid receptacle 2 disposed above the same, and a suitable supply source of water or the like, such as the tank 3, which is preferably disposed at substantially the 75 same level as the tank 1. The tank 1 in operation is preferably filled with a fire extinguishing solution containing a substance that will combine with acid to form extruding gas. In the present instance the 80 tank 1 is filled with a solution of sodium bicarbonate, and water to a level spaced a short distance from the top thereof. The receptacle 2 in operation in the present system is filled with sulfuric acid to a level 85 spaced a short distance from the top 4 thereof, and in which top an opening is provided equipped with the closure 5, by means of which access to the receptacle 2 can be had for the purpose of refilling the same. The 90 receptacle 2 is connected to the tank 1 by the siphon tube S having the short portion 6 disposed in the receptacle 2 which is connected to the long portion 7 by the elbow 8. The elbow 8 is disposed to extend a short 95 distance above the level of the sulfuric acid contained in the receptacle 2 while the lower end of the portion 6 extends almost to the bottom of the receptacle 2, and the lower portion of the portion 7 extends almost to the bottom of the tank 1, it being thus shown that the lower end of the portion 6 is disposed in the sulfuric acid and forms a communication whereby the sulfuric acid may be passed up through the tube S to the tank 100 1 and into the solution of bicarbonate of soda contained therein, the lower end of the portion 7 being disposed in the bicarbonate solution and forming a communication therewith through which the acid may read-

105 110

ily pass to such solution. To maintain the pressure on the acid contained in the receptacle 2 substantially equal to the pressure on the bicarbonate of soda solution contained in the tank 1, the pipe connection P is provided which affords communication between the upper end of the receptacle 2 above the sulfuric acid and the upper end of the tank 1 above the bicarbonate of soda solution and extends from the upper end of the receptacle 2 substantially above the level of the sulfuric acid, down to the upper end of the tank 1 at a line substantially above the level of the bicarbonate of soda solution. The lower end of the pipe connection P is provided with a hand controlled valve 9 whereby the pipe connection may be opened for the purpose of reducing the pressure. Above the valve 9 there is provided a safety connection 10 having a safety valve 11 connected thereto and a pressure gage 12 connected thereto, the pressure gage 12 being provided with a plurality of wire connections 13 which may be connected to any suitable signal whereby the several dangerous degrees of pressure may be readily signaled to the operator.

The tank 1 is also provided with a pipe connection 14 extending practically from a short distance above the bottom of the tank 1 upward to the horizontal pipe connection 15, one end of which is connected to the vertical pipe connection 16 which extends down to and continues in the sprinkler arm 17, which is provided with two heads 18. The heads 18 are equipped in the usual manner with closures composed of metal readily fusible at a slight increase in temperature to open the heads. The pipe connection 16 is connected with the main 19 at a point a short distance above the arm 17, such main 19 being connected to any suitable source of water supply, in the present instance being connected to the tank 3.

The pipe connection 15 is connected with the intermediate pipe connection 20 at its union with the pipe connection 14. This pipe connection 20 has a bore diameter substantially equal to the bore diameter of the siphon tube S and is connected to such siphon tube S at a point a short distance below the lower end of the acid receptacle 2. The connection of the pipe 20 with the pipe connection 15 is disposed at a level a short distance above the level of the connection between the pipe 20 and the siphon tube S, and pipe 20 is provided with an inclination 21 which is equipped with the valve chamber 22 containing the ball float valve 23.

The pipe connection 14 is provided with the pipe connection 24 extending from the pipe connection 14 at a point a short distance above the tank 1 down to and into the tank 1 to afford a communication between the pipe 14 and the inside of the tank

1 above the level of liquid contained therein. The pipe connection 24 is provided with the valve 24' for controlling the same.

The tank 1 is provided with the hand controlled drain cock 25 disposed at its bottom. 70

At the upper end of the vertical pipe P is a horizontal pipe P' communicating with the acid container and siphon receptacle 2 just above the level at which the body of acid will be normally maintained therein, 75 in which pipe is located a check valve of any suitable form 26 which opens toward the pipe P and closes reversely toward the receptacle when the pressure in such receptacle 2 falls below the pressure in the bicarbonate of soda solution tank 1, and also in communication on the same level as P', above the body of acid contained in such tank 2, is a pipe 27 having a cut-off valve 28, and provided between the receptacle and 80 such valve 28 with a check valve 29 opening inward toward the receptacle and preventing escape of the pressure by such valve, even when the valve 28 is open.

In filling the receptacle with acid, the hand-hole cover 5 of the usual form well known in the art, is removed and acid poured in until the level is that shown in Fig. 1, just below the pipes P' and 27, when the apparatus is ready for use. 90

The hand controlled valve 28 is opened when the apparatus is to be used as a wet system, in which case if the apparatus should be set in operation any siphonic action in the siphon tube S will cause a 100 vacuum in the air space of the receptacle 2 and thereupon air is admitted through the check valve 29 and into said chamber and at the same time any pressure thereafter generated in the receptacle 2 will be prevented from escaping except downwardly through the supply pipes 15, 16 and 17 and thence to the sprinkler heads 18 or the hose 33.

When the apparatus is to be used as a 110 dry system, a pressure may be supplied to the same from any suitable source, in the present instance a pipe connection 30 provided with the hand controlled valve 31 is connected to the pipe connection 15. Such 115 pipe connection 30 may be connected to any suitable source of pressure supply, by means of which when the valve 31 is opened and the apparatus is to be used as a dry system, pressure may be fed through said pipe connection 30 to the pipe connection 15 and then throughout the system. 120

The sprinkler arm 17 is provided with a hand controlled valve 32 near its extreme end, which end is connected to a hose 33. By 125 means of this hose 33 when the valve 32 is opened, the system may be operated even when the sprinkler heads 18 are not opened.

When the apparatus is to be used as a wet system, the same is connected to a suitable 130

source of water supply by means of which water may be conveyed to the sprinkler arm 17 and vertical pipe connection 16 to co-operate with the system to maintain proper pressure therein. For this purpose the pipe connection 16 near its union with the pipe connection 15 is provided with a pipe connection 34 which extends over and connects with the top of the water reservoir 3, such 5 pipe connection 34 being disposed at a level above the top of the reservoir 3 and connecting with the pipe connection 16 at a level above the top of the reservoir 3. The pipe connection 34 is provided with a hand controlled valve 35. The pipe connection 19 connecting the pipe connection 16 with the bottom of the reservoir 3 is provided with a hand controlled valve 36.

When the apparatus disclosed in Fig. 1 is 20 to be used as a dry system, the operation is substantially as follows: It will be assumed that the valve 32 is shut off, the valve heads 18 closed, the valves 36, 35, 25, 9, and 28 closed, and the valve 24' opened; water and 25 bicarbonate of soda disposed in the tank 1 to a level which is below the communication of the pipe connection P with the tank 1, sulfuric acid disposed in the receptacle 2 to a level just below the communication of the 30 pipe connection P with the receptacle 2; and the valve 31 opened to permit pressure to be conveyed to the pipe connection 15 from any suitable source. The pressure on the liquid contained in the tank 1 and on the acid contained 35 in the receptacle 2 will be substantially the same, since the pressure will extend from the pipe connection 15 to the pipe connection 14 and then by the pipe connection or by-pass 24 to the tank 1 above the level 40 of the liquid therein, and from such tank 1 through the pipe connection P and the receptacle 2 above the level of the acid. If the pressure is of sufficient magnitude it may force the ball valve 23 into a position to prevent 45 any of the pressure to enter and pass into the siphon tube S. The apparatus is then in condition for operation. Then upon a fire occurring, the temperature adjacent to the heads 18 rising to the required degree, the 50 heads will melt off and permit the pressure to discharge from said sprinkler arm 17 through said heads 18, or, when the said hose is to be used, the valve 32 is opened to permit the pressure to discharge from said sprinkler 55 arm 17, it being understood that in the meantime, or previously at any rate, the valve 31 will preferably be shut off to prevent the supply of any additional pressure, this decrease in pressure will suck up liquid from the tank 60 1 up the pipe connection 14 a considerable distance, and in addition suck the ball valve 22 to permit a passage through the pipe connection for an instant, during which instant the suction will, by means of the pipe connection 21 and the siphon tube S, suck up acid 65

through the short arm 6 of the siphon tube S above the elbow 8, whereupon the liquid will continue to run down the arm 7 and the siphonic action be started.

The ball 23 composing with its casing 22 70 a float-ball-valve is located between the pipes 15 and the pipes S and 7, as clearly indicated in Fig. 1; such float-valve being preferably made extremely light so that the same may be closed by air pressure. And when the 75 siphonic action is started, such valve being very light, the passage of the bicarbonate of soda solution up through the large pipe 14 turning to the right into 15, will cause a diminution of air pressure in the smaller 80 pipe 20 21, which for this reason is bent upward and the pipe 15, placed at a somewhat higher level than is the pipe connecting 22 with 7 and S, and the air trapped between S and 7 and 22, will be sufficient in 85 pressure to maintain the ball-valve 23 against its seat in 22, so as to prevent any entrance of the acid into the pipe 15 by way of 22, 21, and 20; and by this action of the float-ball 90 23 communication is shut off through such connection 20, and furthermore, as soon as such acid enters the liquid contained in the tank 1 it will react on the bicarbonate of soda contained therein to form a gas under pressure which will act on the liquid contained in such tank 1 to extrude the same up through the pipe connection 14 to the pipe connection 15 and through the pipe connections 16 and 17 either out through the heads 18 or out through the hose 33. When the 100 heads 18 are closed, as aforesaid, a small air space will be present in the siphon tube S extending down on both sides of the elbow 8 to shut off the siphon action, and set the same ready for action when the desired decrease of 105 pressure takes place. The contact of the acid with the bicarbonate of soda will produce carbon dioxid, and the pressure generated thereby will be sufficient to expel the solution from the heads 18 at a considerable 110 force.

From the foregoing it will further be seen that as soon as gas is generated in tank 1 by the siphonic action and the pressure raised, such pressure, through the instrumentality of the pipe connection P, will be transmitted to the receptacle 2 and thereby quicken the travel of the acid through the siphon tube S. It will further be seen that as long as the acid passes through the siphon tube S and fills the pipe connection 20 it will maintain the valve 23 against its seat and prevent the passage into the siphon tube S of the liquid that is passing out through the pipe connections 14 and 15, 115 and that since the flowage of the liquid through the pipes 14 and 15 depends on the pressure generated in the tank 1, which is immediately transmitted to the receptacle 2, the pressure on the acid in the pipe 120 130

- connection 20 to maintain the ball in place will always be greater than the liquid flowing out of the pipe connections 14 and 15. Thus the pressure in the pipe connections 14 and 15 can never increase sufficiently to unseat the ball 23 and force back the acid in the pipe connection 20.
- From the foregoing it will further be seen that the siphon action will continue until all of the acid contained in the receptacle 2 will have passed into the tank 1, and that thus the initiation of the action of the present fire extinguisher is very effective and at the same time automatic.
- Pipe connections 14, 15, 16 and 17 are of considerably larger bore diameter than the bore diameter of the siphon tube S and pipe connection 20, so as to form a path of lesser resistance as the liquid is being forced up through the pipe connection 14, and thus facilitate and assure its passage out through the pipe connections 15, 16, and 17, instead of back through the pipe connection 20 to interfere with the action of the siphon S.
- When the apparatus disclosed in Fig. 1 is to be used as a wet system, the operation will be substantially as follows: It will be assumed that the valves 32, 25, 9, 31 and 24' are closed, the valves 28, 35, and 36, opened, the sprinkler heads 18 closed, the water from the reservoir 3 passed through the pipe connection 19 into the pipe connection 16 and arm 17 so that the level of water in the arm 17 will be the same as the level of the water in the reservoir 3. Due to the opening of the valve 28, the pressure of the system in this condition will be substantially atmospheric. And there will be an air space in the siphon tube S just the same as when the apparatus is to be used as a dry system. With this condition of the apparatus, whenever a fire occurs and the temperature adjacent to the heads 18 rises the required amount, the heads 18 will melt off and permit the discharge of the water in the arm 17 and pipe connection 16 through said heads 18, or, when the valve 32 is open, the hose 33 will permit the discharge of water therethrough from the arm 17 and pipe connection 16, and this discharge of water will so reduce the pressure in the system that it will draw liquid in the tank 1 up through the pipe connection 14 and suck acid up the arm 6 over the elbow 8 to start the siphon action. Thereupon the discharge of the solution in the tank 1 will begin and continue the same as with the apparatus when used as a dry system. With the present wet system, after all of the fire extinguishing element contained in the tank 1 has been discharged, the heads 18 or valve 32 still being open, the water from the reservoir 3 may still discharge from such heads 18 or hose 33.
- The embodiment illustrated in Fig. 2 is especially adapted to be used as a wet system and is provided with a tank 1'; receptacle 2', having the top 4' and cover 5'; reservoir 3'; siphon S' having the short arm 6', long arm 7', and elbow 8'; pipe connection 70 P' connecting the receptacle 2' with the tank 1' and equipped with the connection 26', union 10', safety valve 11', pressure gage 12', wire connections 13', pet cock 9'; pet cock 25' at the bottom of the tank 1'; pipe 75 connection 27' connected to the upper end of the receptacle 2' and having the check valve 29'; horizontal pipe connection 15' connected to the vertical pipe connection 16' at one end and to the vertical pipe connection 14' at its other end, the vertical pipe connection 14' extending into the tank 1' and adjacent to the bottom of the tank 1'; pipe connection 20' between the pipe connection 15' and siphon S', such pipe connection 85 20' having the inclination 21' and provided with the valve chamber 22' in which the ball float valve 23' is disposed; all substantially identical with and corresponding in position and function to the parts correspondingly numbered but not primed, in the embodiment illustrated in Fig. 1. In the present embodiment it will be seen there is not provided a valve similar to the hand controlled valve 28 nor a by-pass similar to 95 the by-pass 24, nor pipe connections similar to the pipe connections 30 and 34 of the embodiment illustrated in Fig. 1, these not being required for the present embodiment. The connection between the pipe connection 16' and the reservoir 3' is different than the connection between the pipe connection 16 and reservoir 3 of the embodiment illustrated in Fig. 1, and comprises an auxiliary reservoir 37 having a gage-glass 105 38 disposed on the side of the same and operatively connected to such auxiliary reservoir 37, and both disposed at a level substantially equal to that of the reservoir 3', a pipe connection 39 connecting the lower 110 end of the auxiliary reservoir 37 with a sprinkler arm 40, similar to the sprinkler arm 17, and having the sprinkler heads 41 along its body, and a hand controlled valve 42 at its free end to which is connected the 115 hose 43, a pipe connection 44 connecting the pipe connection 39 with the reservoir 3', there being a hand controlled valve 45 connected to such pipe connection 44 to control the same.
- The operation of the embodiment illustrated in Fig. 2 is substantially as follows: It will be assumed that the valves 9' and 25' are closed, the heads 41 sealed and the valve 42 closed. The valve 45 is at first 125 opened and may remain open if desired, whereupon the water from the reservoir 3' will flow into the pipe connection 39 and arm 40 and up into the auxiliary reservoir 37 to the same level as the water in the reser- 130

voir 3', which level will be indicated by the level gage glass 38. It will be assumed that the siphon tube S' has an air space therein extending through the elbow 8' and the ball 5 float valve 23' disposed in the bottom of the valve chamber 22'. The apparatus is now in condition for use. Upon a fire occurring and the temperature adjacent to the heads 41 rising to the proper point, the 10 sealing material of the heads 41 will melt and open such heads, whereupon the water from the arm 40 may discharge therethrough or else the valve 42 will be opened so that the water may discharge through 15 the hose 43. Immediately upon such discharge of water, the level in the auxiliary reservoir 37 will drop, thereby creating a suction which will draw up liquid through the pipe connection 14' a considerable 20 distance and at the same time through the pipe connection 20' and siphon tube S', the acid will be forced up and across the elbow 8; whereupon the siphonic action will be initiated, and immediately the acid will 25 flow over into the pipe connection 20' and raise the ball 23' up to close the upper opening of the valve chamber and thus prevent the acid from flowing through the pipe connection 20' over into the pipe connection 30 15'. As soon as the acid enters the tank 1' and comes into contact with the bicarbonate of soda, carbon dioxide will be generated and the accompanying pressure will exercise a force as already explained on the liquid to 35 extrude the same up through the pipe connection 14' and out through either the heads 41 or the hose 43. The action of the embodiment illustrated in Fig. 2 will thus be substantially identical with the action illustrated in the embodiment shown in Fig. 1, when it is set to be used as a wet system.

It is obvious that various changes and modifications may be made to the details of construction without departing from the 45 general spirit of the invention.

I claim:

1. A fire extinguishing apparatus having a solution of bicarbonate of soda, sulfuric acid for reacting with said bicarbonate of 50 soda to form a gas to expel said solution of bicarbonate of soda, said acid being maintained separate from said solution of bicarbonate of soda, a siphon tube for conveying said acid to said solution of bicarbonate of soda, a source of water supply, a sprinkler head sensitive to heat, a pipe connection connecting said sprinkler head with said source of water supply, a second pipe connection connecting said first pipe 55 connection with said siphon tube whereby upon the opening of said sprinkler head and the passage therethrough of water a suction will be created to initiate the siphon action through said siphon tube.
- 60 2. A fire extinguishing apparatus having

a solution of bicarbonate of soda, sulfuric acid for reacting with said bicarbonate of soda to form a gas to expel said solution of bicarbonate of soda, said acid being maintained separate from said solution of bicarbonate of soda, a siphon tube for conveying said acid to said solution of bicarbonate of soda, a source of water supply, a sprinkler head sensitive to heat, a pipe connection connecting said sprinkler head with said source of water supply, a second pipe connection connected to said first pipe connection and forming a passage for the bicarbonate of soda to said sprinkler head, and a third pipe connection connecting said second pipe connection with said siphon tube whereby upon the opening of said sprinkler head and the passage therethrough of water a suction will be created to initiate the siphon action through said siphon tube. 70 75 80 85

3. A fire extinguishing apparatus having a solution of fire extinguishing element, an acid for reacting with said fire extinguishing element to form a gas to expel said fire extinguishing element, said acid being maintained separate from said fire extinguishing element, a siphon tube for conveying said acid to said fire extinguishing element, a source of water supply, a sprinkler head sensitive to heat, a pipe connection connecting said sprinkler head with said source of water supply, a second pipe connection connecting said first pipe connection with said siphon tube whereby upon the opening of said sprinkler head and the passage therethrough of water a suction will be created to initiate the siphon action through said siphon tube. 90 95 100

4. A fire extinguishing apparatus having a solution of fire extinguishing element, an acid for reacting with said fire extinguishing element to form a gas to expel said fire extinguishing element, said acid being maintained separate from said fire extinguishing element, a siphon tube for conveying said acid to said fire extinguishing element, a source of water supply, a sprinkler head sensitive to heat, a pipe connection connecting said sprinkler head with said source of water supply, a second pipe connection connected to said first pipe connection and forming a passage for the solution of fire extinguishing element to said sprinkler head, and a third pipe connection connecting said second pipe connection with said siphon tube, whereby upon the opening of said sprinkler head and the passage therethrough of water a suction will be created to initiate the siphon action through said siphon tube. 105 110 115 120

5. A fire extinguishing apparatus having a solution of fire extinguishing element, an acid for reacting with said fire extinguishing element to form a gas to expel said fire extinguishing element, said acid being maintained separate from said

- 6
1,258,465
- fire extinguishing element, a siphon tube for conveying said acid to said fire extinguishing element, a source of water supply, a sprinkler head sensitive to heat, a pipe connection connecting said sprinkler head with said source of water supply, a second pipe connection connected to said first pipe connection and forming a passage for the solution of fire extinguishing element to said 5 sprinkler head, a third pipe connection connecting said second pipe connection with said siphon tube whereby upon the opening of said sprinkler head and the passage therethrough of water a suction will be created to 10 initiate the siphon action through said siphon tube, there being a valve chamber in said third pipe connection, an inclination in said pipe connection, the connection of said third pipe connection with said second pipe connection being at a higher level than the 15 level of the connection of said third pipe connection with the siphon tube, and a float valve in said valve chamber adapted to rise and shut off communication through said 20 third pipe connection as soon as the same is filled with acid carried thereto by the siphon action.
6. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said 30 fire extinguishing element, a source of water supply, a sprinkler head sensitive to heat, a pipe connection connecting said sprinkler head with said source of water supply, a second pipe connection connecting said first 35 pipe connection with said siphon tube whereby upon the opening of said sprinkler head and the passage of water therethrough a suction will be created to initiate the siphon action through said siphon tube.
- 40 7. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a source of water supply, a sprinkler head sensitive to heat, a pipe connection connecting said 45 sprinkler head with said source of water supply, a second pipe connection connected to said first pipe connection and forming a passage for the solution of fire extinguishing element to said sprinkler head, and a third pipe connection connecting said second pipe connection with said siphon tube whereby upon the opening of said sprinkler head and the passage therethrough of water a suction will be created to initiate the siphon action through said siphon tube.
- 50 8. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a source of water supply, a sprinkler head sensitive to heat, a pipe connection connecting said 55 sprinkler head with said source of water supply, a second pipe connection connected to said first pipe connection and forming a passage for the solution of fire extinguishing element to said sprinkler head, a third pipe connection connecting said second pipe connection with said siphon tube whereby upon the opening of said sprinkler head and the passage therethrough of water a suction will be created to initiate the siphon action through said siphon tube, there being a valve chamber in said third pipe connection, an inclination in said pipe connection, the connection of said third pipe connection with said second pipe connection being at a higher level than the level of the connection of said third pipe connection with the siphon tube, and a float valve in said valve chamber adapted to rise and shut off communication through said third pipe connection as soon as the same is filled with the acid carried thereto by the siphon action.
- 60 9. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a source of water supply, a sprinkler head sensitive to heat, a pipe connection connecting said 65 sprinkler head with said source of water supply, a second pipe connection connected to said first pipe connection and forming a passage for the solution of fire extinguishing element to said sprinkler head, a third pipe connection connecting said second pipe connection with said siphon tube whereby upon the opening of said sprinkler head and the passage therethrough of water a suction will be created to initiate the siphon action through said siphon tube, there being a valve chamber in said third pipe connection, an inclination in said pipe connection, the connection of said third pipe connection with said second pipe connection being at a higher level than the level of the connection of said third pipe connection with the siphon tube, a float valve in said valve chamber adapted to rise and shut off communication through said third pipe connection as soon as the same is filled with the acid carried thereto by the siphon action, the level of the fire extinguishing element being 70

- spaced a short distance from the top of said tank, the level of the acid being spaced a short distance from the top of said receptacle, a fourth pipe connection connecting 5 the space of said tank above said fire extinguishing element with the space of said receptacle above said acid whereby the pressure in the receptacle and tank may be maintained equal.
- 10 10. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a source of water supply, a sprinkler head sensitive to heat, a pipe connection connecting said 15 sprinkler head with said source of water supply, a second pipe connection connected to said first pipe connection and forming a passage for the solution of fire extinguishing element to said sprinkler head, a third 20 pipe connection connecting said second pipe connection with said siphon tube whereby upon the opening of said sprinkler head and the passage therethrough of water a suction will be created to initiate the siphon action 25 through said siphon tube, there being a valve chamber in said third pipe connection, an inclination in said pipe connection, the connection of said third pipe connection with said second pipe connection being at a higher 30 level than the level of the connection of said third pipe connection with the siphon tube, a float valve in said valve chamber adapted to rise and shut off communication through said third pipe connection as soon 35 as the same is filled with the acid carried thereto by the siphon action, the level of the fire extinguishing element being spaced a short distance from the top of said tank, the level of the acid being spaced a short distance 40 from the top of said receptacle, a fourth pipe connection connecting the space of said tank above said fire extinguishing element with the space of said receptacle above said acid whereby the pressure in the 45 receptacle and tank may be maintained equal, a safety connection in said fourth pipe connection, a safety valve connected to said safety connection, and a pressure gage connected to said safety connection.
- 50 11. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a source of water supply, a sprinkler head sensitive to heat, a pipe connection connecting 55 said sprinkler head with said source of water supply, and a second pipe connection connecting said first pipe connection with said siphon tube whereby upon the opening of said sprinkler head and the passage of water therethrough a suction will be created to initiate the siphon action through said siphon tube, the level of the water in said second pipe connection being maintained at a lower level than the level of fire extinguishing element in said tank to 60 preserve the sensitiveness of the system. 70
12. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element when a fire occurs, and means for initiating siphon action by 75 said siphon tube for conveying acid to said fire extinguishing element, said initiating means comprising a discharge portion, a pipe connection connecting said discharge portion with said siphon tube, there normally 80 being an air space in said siphon tube to normally maintain the same inoperative, the discharge portion being normally closed, and means for maintaining the pressure in 85 said pipe connection when said discharge portion is closed, the opening of the said discharge portion operating to drop the pressure in said pipe connection thereby to draw up acid a distance through said siphon tube to initiate the siphon action. 90
13. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element when a fire occurs, and means for initiating siphon action by 95 said siphon tube for conveying acid to said fire extinguishing element, said initiating means comprising a discharge portion, a pipe connection connecting said discharge portion with said siphon tube, there 100 normally being an air space in said siphon tube to normally maintain the same inoperative, the discharge portion being normally closed, an air pressure means for maintaining the pressure in said pipe connection 105 when said discharge portion is closed, a second pipe connection for connecting said first pipe connection with a source of gas pressure or the like, means for controlling said second pipe connection, a source of water supply, a third pipe connection for connecting said 110 first pipe connection with a source of water supply, a second controlling means for said third pipe connection, the water supply, when said second pipe connection is shut off from said first pipe connection and said 115 120
- 125 130

- third pipe connection is in communication with said first connection, flowing into said first pipe connection to form pressure therein; and in turn the second pipe connection, 5 when the third pipe connection is shut off from said first pipe connection and said second pipe connection is in communication with said first pipe connection, permitting gas pressure or the like to be supplied to said 10 first pipe connection; the opening of the said discharge portion operating to drop the pressure in said pipe connection thereby to force the acid through said siphon tube to initiate the siphon action.
- 15 14. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a sprinkler arm, fusible heads on said sprinkler arm, a hose 20 connected to said sprinkler arm, control means for controlling the discharge from said sprinkler arm through said hose, a pipe connection connecting said sprinkler arm with said tank, means for supplying pressure to said pipe connection, a second pipe connection connecting the first pipe connection with said 25 tank, means for supplying pressure to said pipe connection, a second pipe connection connecting said first pipe connection with said siphon tube, there being a valve chamber in said second pipe connection, an inclination in said second pipe connection, the 30 connection of said second pipe connection with said first pipe connection being at a higher level than the level of the connection of said second pipe connection with the 35 siphon tube, and a float valve in said valve chamber adapted to rise and shut off communication through said second pipe connection as soon as the same is filled with the acid carried thereto by the siphon action, there normally being an air space in said siphon tube to normally maintain the same 40 inoperative, the opening of said discharge portion operating to drop the pressure in said pipe connection thereby to force the acid through said siphon tube to initiate the 45 siphon action.
15. A fire extinguishing apparatus having a tank for containing a solution of fire extinguishing element, an acid for reacting with said fire extinguishing element to form a gas to expel said fire extinguishing element, a receptacle for containing said acid, a siphon tube for conveying said acid to said fire extinguishing element, a sprinkler arm, fusible heads on said sprinkler arm, a hose 50 connected to said sprinkler arm, control means for controlling the discharge from said sprinkler arm through said hose, a pipe connection connecting said sprinkler arm with said tank, means for supplying pressure to said pipe connection, a second pipe connection connecting the first pipe connection with said siphon tube, there normally being an air space in said siphon tube to normally maintain the same inoperative, the 55 fusible heads and controlling means being normally closed, the opening either of said fusible heads or of said controlling means operating to relieve the pressure in said first pipe connection and thereby to force the acid 60 through said siphon tube to initiate the siphon action.
